UNITED STATES PATENT OFFICE.

WILLIAM HENRY HARGRAVE, OF OLNEY, OREGON.

DESIGN FOR AN EMBLEMATIC BADGE.

Application filed October 8, 1920. Serial No. 415,708. Term of patent 3½ years.

To all whom it may concern:

Be it known that I, WILLIAM HENRY HARGRAVE, a citizen of the United States, residing at Olney, county of Clatsop, State of Oregon, have invented a new, original, and ornamental Design for an Emblematic Badge, of which the following is a specification, reference being had to the accompanying drawing, forming a part thereof.

The figure in the drawing shows an elevation of my emblematic badge in perspective.

The drawing merely illustrates the way in which the essential feature of my design may be incorporated in an emblematic badge.

The essential feature of my design is in the projecting hand thereby suggesting fellowship and that the wearer of the badge is willing to assist in the cause for which it stands.

I claim the ornamental design for an emblematic badge as shown.

WILLIAM HENRY HARGRAVE.
